SAFETY VAULT LOCK.

Application filed October 13, 1926. Serial No. 141,300.

The purpose of our invention is to provide a safety vault lock of simple, durable and inexpensive construction.

More particularly, it is our purpose to provide a vault lock of the kind under consideration having parts which can be mounted on a vault door and door jamb respectively and adapted to be set into position such that when a vault door is swung from opened toward closed position, the vault lock will engage and hold the door in position almost closed in such manner that the lock can not easily be released from outside and yet afford ventilation to any persons who might be in the vault, which device, however, can be easily released from inside the vault.

Another feature of our invention is the provision of a safety vault lock of such construction that when the vault door is moved from closed to open position the mechanism of the lock is automatically "set" for actuation when the door is moved toward closed position.

It is another purpose to provide in such a vault lock novel features of structure enabling us to eliminate the use of springs and affording a device, which is not likely under any circumstances to get out of order or become inoperative.

Another object is to provide such a device, which can be made in a factory at a relatively small cost and which is adapted to be used in a standard construction for installation on vaults of different kinds.

With these and other objects in view, our invention consists in the construction, arrangement and combination of the various parts of our device, whereby the objects contemplated are attained, as hereinafter more fully set forth, pointed out in our claims, and illustrated in the accompanying drawings, in which:

Figure 1 is a vertical, sectional view of a portion of a vault door jamb equipped with a safety vault lock embodying our invention, the parts being shown in position ready for closing the vault door for the night, the door and keeper being shown in dotted lines.

Figure 2 is a vertical, sectional view of portions of the jamb and door and of the latch and keeper structure showing the parts in position when the door is closed for the night.

Figure 3 is a similar view showing the

parts in their positions assumed after the vault door has been opened and the lock mechanism is set for operation when the vault door is swung toward closed position.

Figure 4 is a vertical, sectional view of portions of the door and door jamb, the latch and keeper structure being shown in side elevation with the parts in the position, which they assume when the door has been swung toward closed position and has actuated the latch to cause it to drop to position for holding the door slightly open.

Figure 5 is a detail, sectional view taken on the line 5—5 of Figure 4.

Figure 6 is a perspective view of the latch; and

Figure 7 is a perspective view of the trigger forming a part of our device.

An understanding of the construction, operation and purpose of our device may be facilitated by briefly explaining the circumstances which give rise to a need of such a lock.

When a daylight bank robbery occurs, the bandits sometimes shut bank employees in the vault with the consequent possible suffocation of such employees. Sometimes employees are in the vault or may go into the vault, and yet they do not desire to close the door entirely on account of suffocation.

It is our general purpose to provide a safety lock, which can be set so that if such a daylight robbery occurs, the employees may go into the vault, swing the door toward closed position, whereupon the device will be automatically actuated for locking the door in slightly open position in such manner that the robbers can not conveniently open it.

Similarly, if the employees are forced into the vault by the robbers, and the robbers swing the door toward closing position, the door will be caught and latched in almost closed position.

In the accompanying drawings, we have used the reference numeral 41 to represent the front wall structure of a bank vault or the like forming a door jamb, to which is hinged in the ordinary way the door E.

The jamb and door usually have their coacting edges stepped as at 42 and 43.

We provide a latch structure mounted in the housing A open at its lower portion and front end and provided at its front end with the securing flange 18. The flange 18

is adapted to be secured to the inner face of the jamb 41 just above the door opening by bolts 27, as shown for instance in Figure 5.

Mounted in the housing A is a latch B in the form of a solid block, having at one end the transverse pivot hole 2 to receive the pivot pin 28 mounted in the side walls of the housing A near the rear end thereof.

Projecting forwardly from the upper, forward part of the block forming the latch B is a hook 3.

Between the forward portion of the hook 3 and the front face of the latch B is a transverse notch or slot 6. The front face 15 of the block of the latch B forms a shoulder 5, which when the parts are installed and the latch is extended forwardly from the pivot pin 28, extends downwardly below the hook 3, as clearly shown for instance in 20 Figure 1.

In one side of the latch B is formed a slot 10 extending from the lower face of the latch block upwardly for a substantial distance and curved on the arc of a circle having its center at the center of the hole 2.

A stop pin 29 is mounted in one wall of the housing A and projects into the slot 10 and serves to limit the downward, swinging movement of the latch by gravity.

30 The opposite side face of the latch B is cut away as at 7 to allow room for the trigger C between the latch block and the adjacent wall of the housing A.

The trigger C has generally the form of a triangle with its hypotenuse edge, however, having the form of a re-entrant angle.

The corners of the trigger are preferably rounded as shown. Near the corner 14, the trigger is provided with a transverse hole 40 17 to receive a pin 28^a, projecting from the side wall of the housing A, and thus pivotally supporting the trigger with its hypotenuse edge forward. (See Figure 4.)

Projecting from the side face of the latch 45 B near the shoulder 5 are spaced pins 8 and 8^a adapted to cooperate with the trigger C.

In the hypotenuse edge of the trigger C is a notch 12, as shown.

Secured to the top of the door is a keeper 50 member D, projecting inwardly and having near its inner end spaced up-turned flanges 30 and 31.

The keeper member may be provided with a slot 33 as shown, and the keeper member 55 is fastened to the door by means of screws 34. The flange 30 is inclined upwardly and toward the door as shown in Figure 3.

We will now describe the operation of our improved safety vault lock and in making 60 such description will clear certain features of construction.

The stop pin 29 is so arranged that when the latch B swings downwardly by gravity, its downward movement is limited to a position 65 where the hook member 3 projects be-

low the housing A in about the position illustrated in Figure 4.

The trigger is so supported with relation to the latch that after the pin 8 clears the point 14, the trigger will drop to normal position, as shown for instance in Figure 1 or Figure 4, whereupon the pin 8 will engage the edge 13 of the trigger C near the shoulder 14.

The pivot pin 28^a will then be slightly below the line extending between the pin 28 and the pin 8.

The arc of travel of the pin 8 will be different from the arc of travel of the corner 14 and the pin 8 will bind on the trigger C 80 and consequently the latch B will be held in its raised position, the parts then being as shown in Figure 1. This is the position, which they should have before the door E is closed for the night.

The mechanism is then set so that when the door is moved to closed position from its open position, the latch B will clear the flanges 30 and 31 of the keeper.

As the door moves to closed position, the flange 31 engages the trigger C as shown in Figure 1, swinging it inwardly in the vault and swinging the corner 14 downwardly, so that the latch B may drop until its lower face engages the flange 30, the parts being so arranged that the flange 30 prevents the latch B from dropping to its lower limit of movement.

The corner 16 of the trigger clears the flange 31 and will ordinarily drop toward the flange 30, and the parts assume the positions shown in Figure 2.

It will be understood that there is some slight variation in the positions of the parts depending upon the different installations; for instance, the flanges 30 and 31 will in different installations be spaced different distances inwardly from the door E.

Assuming then that the parts are in the position shown in Figure 2 with the door closed, and that in the morning when the door of the vault is opened, the flanges 30 and 31 sliding along the lower face of the latch B will raise it and the flange 31 engaging the trigger C will swing it forwardly or outwardly toward the door opening, until the corner 14 clears the pin 8, whereupon the latch will drop slightly, and the pin 8^a will drop into the notch 12, and engage the forward wall thereof, as shown in Figure 3.

The friction of the parts will hold the latch B raised as shown in such figure.

The arrangement and size of the parts is such that the corner 16 of the trigger C projects downwardly below the housing A slightly, as illustrated in Figure 3.

The parts are then in position set to be actuated, if for example, a robber should force the employees of the bank into the

vault and swing the door toward closed position, with the intent of locking the employees in the vault.

As the door moves toward closed position, 5 the flange 31 engages the corner 16 of the trigger C, swinging it downwardly and inwardly in the vault until the pin 8^a clears the wall of the slot 12, whereupon the latch B drops to its position shown in Figure 4 10 with the hook 3 overhanging the outer face of the flange 31 and with the flange 31 received in the slot 6.

The door is then in position almost closed as illustrated in Figure 4.

15 The abutment of the flange 31 against the shoulder 5 will prevent any further closing movement of the door and the hook 3 will prevent opening the door. Those on the inside of the vault may readily release the hook 20 3 by raising the latch B, but this is impossible to do from the outside without a special tool.

25 Any one in the vault therefore will be protected against suffocation and against attack in any ordinary way from the outside.

After the departure of the robbers, the door may be opened, and the persons in the vault may release themselves.

30 The flange 30 when used serves two purposes. In the first place, it is possible when the door is locked in nearly closed position as shown in Figure 4, to prevent the use of any straight instrument or nearly straight instrument for releasing the lock and this is an important function. It also serves the function of preventing the latch from dropping to its lowermost position when the door is closed as illustrated in Figure 2. In some installations, this is not important. In some 35 cases, however, the keeper D must be so installed that when it is at its innermost limit of movement, as shown in Figure 2, it would hold the trigger in such position that if the latch were allowed to drop to its lower limit, the pin 8 would engage the corner 14, and the parts might accidentally become locked. Any such accidental locking is prevented when the flange 30 holds the latch up above 40 the lower limit of movement.

50 It will thus be seen that we have provided a safety vault lock of very simple and relatively inexpensive construction, which can be easily and conveniently set before a vault door is closed, so that when the door is closed, the device will be in such position that upon opening the door, the parts will be automatically moved to what we may call their primary set position. This is the position shown in Figure 3. The position is 55 such that when the door is swung toward closing position, the device will be automatically actuated for engaging and locking the door in position slightly open.

60 One feature of our invention, which we consider important, is the fact that the parts

are connected and actuated by gravity for moving to locking position, so that no springs are employed, and there is no danger of the device becoming inoperative because of the failure of the springs. At the same 70 time, it is to be noted that the pivot point of the latch is such that when the shoulder 5 drops so as to project even slightly into the path of the keeper on the closing door, the engagement of the flange 31 with the shoulder 5 will tend to force the latch downwardly to full locking position.

The latch is mounted at the top of the door jamb for such gravity operation, and this has another advantage in that it is almost 80 entirely out of sight and in a position where it is least likely to attract the attention of robbers.

Furthermore, when the device is set for operation, the parts are almost entirely 85 housed within the member A, so that it is difficult to quickly secure an understanding of their structure and operation.

By mounting the device above the door, it can be fastened to a very solid part of the 90 jamb.

It should perhaps be explained that when a safety vault lock of this kind is installed, the bank is furnished with a special tool, 95 which will permit the releasing of the lock from the outside. Such a tool would, of course, not be available to the robber. This tool can be used in case the door should be closed accidentally when no one was inside the vault. But if there is a bank employee 100 inside the vault, he may push on the door and cause the latch to bind so that it can not be opened with the tool from the outside.

We claim as our invention:

1. A safety vault lock adapted to be used 105 with a vault door and jamb, comprising a pivotally mounted latch having a hook member at one end with a shoulder adjacent thereto and having near said shoulder spaced projecting pins, a trigger pivotally supported at the side of said latch having a shoulder adapted when the trigger is in normal position to coat with one of said pins for holding the latch raised, said trigger having a portion which when it is in such position projects into the path of the flange of the keeper hereinafter mentioned and being provided with a notch adapted in another position of the trigger to coat with the other pin for holding the latch raised and the trigger with a portion projected into the path of said keeper, combined with a keeper having a flange for coating with said trigger and latch, whereby when the latch is supported on a jamb and the keeper on a door and the latch is in its last-described position and the door is moved toward closed position, the flange on the keeper will actuate the trigger for releasing the latch for causing said hook to drop over said flange with 115 120 125 130

the flange received in the notch in the latch.

2. A safety vault lock adapted to be used with a vault door and jamb, including a latch adapted to be mounted on the jamb and a keeper adapted to be mounted on the door and a trigger, said trigger and latch having coacting parts whereby they may be set in position with the latch raised and a portion of the trigger projecting into the path of the keeper, so that when a door is swung toward closed position the keeper will engage the trigger and release the latch and the latch will engage the keeper for locking the door in nearly closed position.

3. In a safety vault lock, a keeper and a latch mechanism adapted to be mounted on a door and door jamb respectively, said latch mechanism comprising a pivoted latch member, means for limiting the pivotal movement of the latch member, a pivoted trigger, said trigger and latch member having coacting means whereby they may be set in position where the trigger is in the path of the keeper and adapted to be engaged by the keeper when the door is swung toward closed position for releasing the latch member, said latch member being adapted to then drop by gravity for engaging the keeper for holding the door in slightly ajar position.

4. In a safety vault lock, a keeper and a latch mechanism adapted to be mounted on a door and door jamb respectively, said latch mechanism comprising a pivoted latch member, means for limiting the pivotal movement of the latch member, a pivoted trigger, said trigger and latch member having coacting means whereby they may be set in position where the trigger is in path of the keeper and adapted to be engaged by the keeper when the door is swung toward closed position for releasing the latch member, said latch member being adapted to then drop by gravity for engaging the keeper for holding the door in slightly ajar position, said latch member and trigger having coacting parts, whereby they may be set to position for permitting the closing of the door without permitting the latch to engage the keeper.

5. In a safety vault lock, a keeper and a latch mechanism adapted to be mounted respectively on a door and door jamb, said keeper having a pair of spaced upwardly projecting flanges, said latch mechanism having a latch member pivoted to drop by gravity to keeper engaging position, means for limiting the pivotal movement of the latch member, a pivoted trigger, said trigger and latch member having parts adapted to coact for setting them in position whereby the latch is held raised and a portion of the trigger projects into the path of the keeper, whereby when the door is moved toward closed position the trigger will be actuated for releasing the latch member, said latch member having a slot which will there-

upon receive one of said flanges for locking the door in nearly closed position.

6. In a safety vault lock, a keeper and a latch mechanism adapted to be mounted respectively on a door and door jamb, said keeper having a pair of spaced upwardly projecting flanges, said latch mechanism having a latch member pivoted to drop by gravity to keeper engaging position, means for limiting the pivotal movement of the latch member, a pivoted trigger, said trigger and latch member having parts adapted to coact for setting them in position whereby the latch is held raised and a portion of the trigger projects into the path of the keeper, whereby when the door is moved toward closed position, the trigger will be actuated for releasing the latch member, said latch member having a slot which will thereupon receive one of said flanges for locking the door in nearly closed position, the other of said flanges being then between the latch mechanism and the opening between the door and the jamb.

7. In a safety vault lock, a keeper and a latch mechanism adapted to be mounted on a door and door jamb respectively, said latch mechanism comprising a pivoted latch member, means for limiting the pivotal movement of the latch member, a pivoted trigger, said trigger and latch member having coacting means whereby they may be set in position where the trigger is in path of the keeper and adapted to be engaged by the keeper when the door is swung toward closed position for releasing the latch member, said latch member being adapted to then drop by gravity for engaging the keeper for holding the door in slightly ajar position, the latch member having a keeper receiving slot, the walls of which in full locking position are inclined from vertical, said latch member and trigger having coacting parts, whereby they may be set to position for permitting the closing of the door without permitting the latch to engage the keeper.

8. In a safety vault lock, a keeper and a latch mechanism adapted to be mounted on a door and door jamb respectively, said latch mechanism comprising a pivoted latch member, means for limiting the pivotal movement of the latch member, a pivoted trigger, said trigger and latch member having coacting means whereby they may be set in position where the trigger is in path of the keeper and adapted to be engaged by the keeper when the door is swung toward closed position for releasing the latch member, said latch member being adapted to then drop by gravity for engaging the keeper for holding the door in slightly ajar position, the latch member having a keeper receiving slot, the walls of which in full

locking position are inclined from vertical, one of said walls forming a shoulder, said latch member being so pivoted that when the shoulder projects into the path of the keeper to any degree the contact of the keeper with the shoulder tends to force the latch to full locking position, said latch member and trigger having coacting parts, whereby they may be set to position for 10 permitting the closing of the door without permitting the latch to engage the keeper.

9. In a safety vault lock structure adapted to be used in connection with a vault door element and jamb element, the combination 15 of a keeper adapted to be mounted on one of said elements with a movable latch mem-

ber adapted when in operative position and when the door is moved toward closed position to engage with the keeper for locking the door against further closing and against 20 opening movement, a member cooperating with said latch for holding it inoperative, said members being so arranged that when the second member is set to hold the latch member in operative position and the door 25 is opened, the keeper will engage one of said members for rendering the second member inoperative and for permitting the catch member to move to operative position.

Des Moines, Iowa, September 24, 1926.
